UNITED STATES PATENT OFFICE.

GEORGE A. FAIR, OF DETROIT, MICHIGAN.

WINDOW.

1,359,975.

Specification of Letters Patent. Patented Nov. 23, 1920.

Application filed October 16, 1916. Serial No. 125,814.

To all whom it may concern:

Be it known that I, GEORGE A. FAIR, a citizen of the United States, and residing at Detroit, in the county of Wayne and State 5 of Michigan, have invented a new and Improved Window, of which the following is a specification.

The present invention has reference to a window and among its important features 10 are a window frame and a pair of mutually counterbalancing vertically slideable sashes so arranged that when the sashes are open a short distance, without, however, uncovering the window opening at the top or bottom, 15 passages properly protected from rain and wind, are formed at top and bottom for the admission and escape of air, together with means whereby the sashes are prevented from being opened further from the 20 outside, the object being to secure ventilation at all times without danger of entrance by unauthorized persons; a window frame and a lower sash vertically slideable therein, 25 said sash having a ventilating passage through its lower rail which, when the sash is in lowermost position, is entirely concealed and closed by the sill and which, when the sash is elevated, is opened before the lower edge of the lower rail clears the 30 window sill,—in other words, before the window opening is uncovered; means adapted 35 to be pocketed in said lower rail and also adapted to be extended from the inner side thereof whereby the entering current of air is directed upwardly; upper and lower sashes arranged to slide vertically, and a casement sash carried on the outside of said lower sash, whereby a dead air space is formed, the casement sash preferably being 40 removable; a sliding sash frame in which a casement sash is mounted to swing about a vertical axis together with a second casement sash supported on the outside of the first mentioned casement sash in such manner 45 as to be capable of swinging about a vertical axis in respect to the latter whereby a dead air space is formed and whereby access may be readily had to the panes for cleaning purposes; a pair of vertically slideable 50 sash frames the upper of which is of considerably less height than the lower, each of the sash frames carrying a casement sash, whereby, when the casement for the lower sash frame is opened, the casement for the 55 upper sash frame may be swung inwardly

through the opening to afford ready access to the outer surfaces of the panes for washing; a pair of vertically slideable sash frames the upper of which is of considerably less height than the lower, each of the sash frames carrying both inner and outer casement sashes whereby dead air spaces are formed and whereby ready access to the outer surfaces of the panes may be had in the manner stated. The invention further 60 65 consists in the details of construction shown, described and claimed.

In the drawings, Figure 1 is an elevation taken from the outside of the building, the outer casement sashes being shown. Fig. 2 70 is a similar view from the interior. Fig. 3 is a vertical section corresponding thereto, parts being broken away. Figs. 4, 5 and 6 are enlarged vertical sections, respectively, 75 in the vicinity of the upper rail of the upper sash, of the meeting rails, and of the lower rail of the lower sash. Fig. 7 is a horizontal section, the sashes being lowered in registration with each other.

The sill of the window frame or casing 80 (Fig. 3) is formed of an outer portion 1 and an inner portion 2, each preferably of channel cross-section, the inner portion being considerably higher than the outer—manifestly both portions may be made of one 85 piece; the lintel comprises the structure (the details of which may be varied widely) designated as a whole by 3, together with the detachable sealing strip 4; while the stiles are, for the most part, formed of the 90 main channel-shaped frame members 5 and the jamb casings 6. It will be observed that the members 5 have welded or otherwise secured to their outer faces sash guiding flanges 8; that there is likewise provided at their inner edges rigidly secured sash guiding flanges 9, which may be part of angle irons 10; and that resilient parting strips 11 of substantially channel cross section and of considerable width, measured on 95 a line perpendicular to the plane of the window, are interposed midway between the flanges 8 and 9. One edge portion 12 of each of the parting strips is preferably free.

The channels thus formed in the frame 105 constitute guides for vertically slideable sashes, the construction of which will be more readily understood when it is remembered that each of the sashes carries a casement (in fact two casements, in the embodied 110

ment shown) which is capable of swinging in respect thereto about a vertical axis. It will also be helpful to remember that the casement for the lower sash is of greater 5 dimension both horizontally and vertically than that of the upper sash.

The stiles of the upper sliding sash are formed of outwardly opening channel members 13 having sealing strips 14 welded 10 along the inner edge of their front faces. The upper rail 18 may be channel shaped, or of box shape as shown, whereas the lower rail includes a substantially L section which may be formed by angle irons, the 15 upturned flange 19 of which constitutes a sealing strip for the casement while the downturned flange 20 forms part of the means for sealing the joint between the meeting rails of the sashes.

20 Pivoted to the inner edge of one of the stiles 13—14 at 21 is an inner casement having its stile nearest the pivots formed of channel members 22 and 23 arranged back to back, its other stile including the 25 out-turned channel member 24, to the rear face of which is secured the inwardly projecting plate 25. In like manner, the upper and lower rails are respectively formed of out-turned channel members 26—28 and 30 plates 29—30 that form seats for the pane 31 against the front face of which are retaining strips 32 of suitable construction. The stile 22—23 has supported upon its outer face pivots 34 upon which is mounted 35 an outer casement comprising an upper rail 35, a lower rail 36 and a stile 38, all of which may be of substantially L shape in cross section, whereas its stile adjacent the pivots is preferably formed of an angle bar 39, one 40 leg of which, when in closed position, overlaps the edge of the member 23. The pane 40 and retaining strips 41 complete the casement.

45 For the purpose of locking the outer casement in the inner casement and the latter in the sliding sash frame both at top and bottom, the sash frame is provided with sockets 42 in which the ends of locking bars 43, that are carried by the inner casement and pass 50 through perforated guides 44 thereon, are adapted to be projected. These bars are also adapted to pass through perforations 45 in stirrups or other members 46 rigid with the upper and lower rails of the outer 55 casement, it being understood that the members 46 are in turn adapted to swing into the inner casement through appropriate slots in the outer wall of the lower rail. The locking bars 43 are connected to a rotatable 60 crank 48 which is operated by a hand lever 49.

65 The lower sliding sash frame is preferably formed of a box-like upper rail 50 having a flange 51 spaced therefrom to co-operate with the flange 20 for sealing pur-

poses together with a downwardly projecting sealing flange 53. It is also preferably provided with a cap plate 54 which may lie just above a roller shade 55 and protect the latter from dust. Stiles 58—59, which correspond substantially to the stiles 13—14 except that the channels 58 are more shallow than the channels 13, are guided by the flanges 9 and 12. The lower rail is formed of a box-like structure 60 having its lower 70 side provided with a screen 61 and its inner side for the most part removed to form a free passage through which air may enter when the parts are in the position shown in Fig. 3. A deflector, preferably in the form 75 of a portion 62 of a cylinder having ends 63, is arranged to swing on pivots 64 carried by the rail from a position wherein it is enclosed by the rail (as indicated in dotted lines, Fig. 3) to a position in which it projects therefrom and directs the entering air current upwardly, as shown by the arrows, 80 Fig. 3. Spring clips 65 and 66 with which a projection 68 on the deflector engages, 85 retain the latter in the positions stated, and appropriate hand grips 69 on the interior 90 of the deflector afford a ready means for withdrawing the latter.

95 Adjacent the upper limit of travel of the upper sash the frame 3—5—8 carries on its outer face a hood of suitable construction, preferably a plate 71 of part cylindrical shape having ends 72, the lower face of the hood being provided with a screen 73. Thus when the upper sash is lowered, air may 100 escape from the room through the passage and screen.

105 The elements 79—80—81—82—83—84—85—86—88—89—90 of the inner casement correspond, except in matter of size as hereinafter stated, respectively, to the elements 21—22—23—24—25—26—28—29—30—31 and 32 of the inner casement of the upper sash, and the elements 91—92—93—94—95—96—97 likewise correspond, respectively, to the elements 34—35—36—38—39—40 and 41 of the outer casement of the upper sash. In similar manner the locking mechanism 100—101—102—103—104—105—106 is substantially the same as the mechanism 110 42—43—44—45—46—48—49 heretofore described.

115 Connecting the sashes and passing over suitably supported pulleys 108 are chains 109 whereby they are caused to tend to mutually counterbalance each other, it being understood that the upper rail of the upper sash is preferably supplied with heavy material sufficient to render the weights of the sashes substantially equal. One element of 120 each side of the window frame, for example, the member 10, is notched or socketed at a plurality of levels to receive the end of a latch plunger 112 which is pivoted to an operating bar 113 and slides through a per- 125 130

foration in a bracket 115 rigid with the channel member 58. The bar 113 is in turn pivoted at 116 to the front or outer flange of the channel member 58 and swings horizontally in a slot 118 (Fig. 2) formed in the rear or inner flange of the same member, but the plunger is normally drawn toward the member 10 by a spring 119 anchored in the bracket 115. The operating bars project into the room and form hand grips 120.

In order to prevent the outer casements from being removed by unauthorized persons when the casements are closed, the sliding sash frames 13—14 or 58—59, as the case may be, are provided with brackets 122 (Fig. 1, not shown in other figures) which overlie the hinges 34 and 91 and prevent the component elements thereof from being disengaged from one another. While shown above but one of the hinges of each casement, the brackets may, of course, be employed above the remaining hinges.

Operation: When the sashes are fully closed both entrances to the ventilating passage through the lower rail are closed by the sill, thus insuring the formation of a dead air space in the lower rail and preventing such gusts of air as might pass in through seams were the passage closed at but one end. The deflector being concealed, the appearance of the lower rail is substantially the same as that of ordinary constructions. Now assuming that the lower sash is raised a distance sufficient to enable the deflector to be withdrawn but insufficient to cause the lower rail to clear the sill, air passes in at the bottom and out at the top and rain is effectually excluded—likewise unauthorized entrance is prevented by the engagement of the plungers 112 with the walls of the appropriate socket in the frame. The window is therefore as safe in ventilating position as ordinary windows when entirely closed, thus enabling a room or building to be, in effect, closed without interfering in any way with the circulation of air—a feature that does away with the reason by which timid persons are impelled to entirely close the windows when alone at night, and also makes it practical to maintain ventilation even when the house is left closed for long periods.

When it is desired to clean the panes of the lower sash, the levers 106 are turned

enough to withdraw the bars 101 from the sockets 100, whereupon both inner and outer casements are swung inwardly on pivots 79, which affords access to the outer surface of the outer casement, after which a further movement of the lever 106 releases the outer casement from the inner and enables the former to be swung outwardly on pivots 91 to allow access to the other surfaces of the glass panes. The casements of the lower sash being swung inwardly and the upper sash being in registration with the lower, the panes of the upper sash casements (because of the less dimensions thereof) may be swung inwardly through the opening in the lower sash and cleaned in a manner similar to that just described.

Many features of the invention are applicable to doors as well as windows, and regardless of the particular material or construction of the individual parts; I do not, therefore, wish to be limited except as indicated by the subjoined claims.

I claim:

1. In combination, a window frame having a sill, a sash slidable in said frame adjacent the sill and including a lower rail formed with a ventilating passage having openings in the bottom and in the inner side of said rail, the height of said opening in the inner side of the rail being less than the height of the sill, a screen secured to the bottom of said lower rail across the opening therein and a deflector comprising one fourth of a cylinder mounted in said passage and adapted to swing out through the opening in the inner face of said rail on its center of curvature.

2. In combination, a window frame having a sill, a sash slidable in said frame adjacent the sill and including a hollow lower rail constituting a ventilating passage having openings in the bottom and inner side of said rail, the height of the opening in the inner side being such that it is entirely closed by the sill when the sash is in its low position, a screen secured to the bottom of said lower rail across the opening therein and a deflector within said lower rail and adapted to swing from said side opening, and means to hold the deflector in its projecting and withdrawn positions.

GEORGE A. FAIR.
